UNITED STATES PATENT OFFICE.

FRANK S. POLLEY, OF WEST PULLMAN, ILLINOIS, ASSIGNOR TO THE WHITMAN & BARNES MANUFACTURING COMPANY, OF AKRON, OHIO, A CORPORATION OF OHIO.

HAY-CARRIER.

No. 909,661.

Specification of Letters Patent.

Patented Jan. 12, 1909.

Application filed July 13, 1908. Serial No. 443,291.

11.11

To all whom it may concern:

Be it known that I, FRANK S. POLLEY, a citizen of the United States, residing at West Pullman, in the county of Cook and 5 State of Illinois, have invented a certain new and useful Improvement in Hay-Carriers, of which the following is a full, clear, concise, and exact description, reference being had to the accompanying drawings, 10 forming a part of this specification.

My invention relates to carriers, and has for its object the provision of improved means for controlling the load in transit.

My invention will be exhibited in the accompanying drawings, showing the preferred embodiment thereof, in which—

Figure 1 is a side elevation of such preferred embodiment. Fig. 2 is an end elevation. Fig. 3 is a sectional elevation on line 20 3 3 of Fig. 2. Fig. 4 is a plan view of the structure. Fig. 5 is a sectional view on line 5 5 of Fig. 1. Fig. 6 is a detail view on line 6 6 of Fig. 4.

Like parts are indicated by similar characters of reference throughout the different figures.

The wheeled carriage is of any suitable construction, the carriage shown including two parallel vertically disposed wheel supports or frame members *a a* that are integrally formed with outwardly extending flange plates *b b* which are rigidly fastened to angle irons *c c* (see Fig. 3). The wheels *d* are suitably mounted between the frame 30 members *a* and are adapted to ride upon tread portions *e e* of an overhead track. One of the frame members *a* has slideable engagement with the angle irons *c*, so that the wheels upon one frame member may be 35 adjusted with respect to the wheels upon the companion frame member to suit the width of the track over which the wheels are to run. To this end, the angle irons *c* may be provided with slots *f* disposed longitudinally thereof and bolts *g* passing through these slots and the flange portion *b* of the associate frame element *a*.

The structure thus far described constitutes the carriage provided for the purpose 50 of transferring the hay from place to place.

A swinging frame depends from the carriage, the carriage having two downwardly projecting bearings *i*, preferably integrally formed with the angle irons *c*, a shaft *k*,

preferably the shank of a bolt, being supported by said bearings, and, in turn, affording a pivotal support for the latter frame work, whereby said frame work is brought into swinging relation with the carriage. The frame work includes the two inverted 60 members *l*, the sleeves *m* intervening between the lower ends of the frame members *l* and bolts *n* passing through the sleeves, which sleeves, together with said bolts, act as distance-preserving devices to maintain 65 the lower ends of the frame members *l* a proper distance apart. The sleeves *m* also serve to act as shafts upon which the rear sheave *o* and the forward sheave *p* may turn. The draft rope *q*, after being passed over 70 the sheaves, has swivel connection at *r* with the carriage frame work, the other end of the draft rope being adapted for attachment to a draft animal or some mechanism for exerting pull upon the rope, it being preferable to direct the rope over the pulley *p* at an angle of about forty-five degrees to the horizontal, the rope passing over suitable guiding means for preserving this angle. It is to be understood that fork or sling 75 pulley mechanism is provided to ride over the portion of the rope intervening between the rear pulley *o* and the place *r* of rope attachment.

The swinging frame work carries a member *s* of a rope clutch, this member being desirably fixed with respect to said frame work, and, in the embodiment of the invention shown, also constituting a distance piece 80 between the upper portions of the frame elements *l*. The carriage supports a clutch member *t* complementary to the clutch member *s*, the clutch member *t* being pivotally mounted at its forward end upon the carriage structure, this mounting being located 85 forward of the shaft *k*. The upper ends of links *u* are swingingly connected with the clutch member *t* at the rear of the pivotal connection of said clutch member with the carriage structure, the lower ends of said 90 links having swinging connection with the frame work to the rear of the shaft *k*. The clutch members *s* and *t* have their opposing faces provided with curved recesses to afford a suitable passage through which the 95 rope may travel between the clutch members.

The operation of the sheave and rope clutch mechanism thus far described is as

follows: When the rope *q* is subject to draft, the frame work will be moved in a clockwise direction (looking at the structure as it is viewed in the drawings), whereby the 5 links *u* will be elevated, thereby to lift the pivoted clutch member *t* so as to widen the channel between the clutch members *s* and *t*, so that the rope may freely pass between said clutch members while lifting the load 10 which is supported by the active pulley *o*, the pulley *p* serving as a guide for the rope. Thus during all of the time that the rope is being pulled to lift the hay, the clutch members *s* and *t* are maintained in their 15 separated relation, for the purpose which has been stated. When draft upon the rope *q* ceases, the load carried by the rope swings the frame work in a counter-clockwise direction, this tendency being exerted by reason of the engagement of the said rope with the pulley *o*. The links *u* are thereupon drawn downwardly, whereby the clutch member *t* is forcibly engaged with the rope 20 *q* by the load of hay, which thus acts to prevent its own descent. When the hay has been raised to a suitable elevation, the draft rope may be uncoupled from the animal or the means by which the rope is pulled, whereafter the shifting ropes *v* attached to 25 the carriage, may be pulled to move the carriage along its track, thereby to shift the sheave mechanism and the load of hay it carries to the place where the hay is to be deposited, the hay then being released by 30 tripping the sling or fork mechanism, as is well understood by those familiar with the art. It may be desired on occasion to lower the hay as it is being moved to the place of deposit; for instance, to clear beams. This 35 40 temporary lowering of the load in transit is accomplished by momentary separation of the clutch member *t* from the clutch member *s*, which momentary separation may be conveniently brought about by the elevation 45 of the rear end of the clutch member *t*, which elevation is desirably accomplished by means of a pull exerted upon the free end of a trip rope *w* which passes over a pulley *x* and is connected at its other end to a rearward ex- 50 tension of the clutch member *t*. The trip rope *w* may also be pulled to separate the clutch member *t* from the clutch member *s* when the rope is to be pulled down over the sheave *o*, for the purpose of returning the 55 fork or sling pulleys to the wagon from which the hay is being unloaded.

The portions of the clutch members *s* and *t* which margin the curved recesses therein are desirably toothed, the teeth upon one 60 clutch member being adapted to mesh with the teeth upon another clutch member when the draft rope has been worn sufficiently thin. The purpose of providing these teeth is to enable a contraction of the rope pas- 65 sage afforded by the clutch members while at

the same time maintaining the rope-engaging friction surface in each clutch member as large as possible. In this way the rope is prevented from being unduly flattened by the clutch members when gripping the same 70 while at the same time the rope is well gripped even though it is worn thin.

The distance between the axis of the shaft *k* and the axis about which the clutch member *t* moves, is preferably equal to the distance 75 between the pivotal axes at the ends of the links *u*, whereby the clutch member *t* is always maintained in parallel relation with the clutch member *s*. In this way a very long rope-gripping surface is afforded, 80 whereby the rope may be firmly held without being crimped.

In the preferred embodiment of the invention, the plane of rotation of the sheaves *o* *p* is transverse to the line of travel of the 85 carriage, whereby pull may be exerted upon the draft rope without causing the travel of the carriage upon its track.

While I have herein shown and particularly described the preferred embodiment of 90 my invention, I do not wish to be limited to the precise construction shown, as changes may readily be made without departing from the spirit of the invention.

Having thus described the preferred embodiment of my invention, I claim as new 95 and desire to secure by Letters Patent the following:—

1. In a carrier, the combination with a carriage, of a draft rope for lifting the load, 100 a pair of draft rope engaging sheaves, a frame work for said sheaves having swinging mounting upon the carriage at a location between said sheaves, the parts being so related that the draft rope swings the frame work in one direction when pull is exerted thereon to lift the load, and swings the frame work in the opposite direction when the elevated load is relieved of lifting force, a draft rope clutch between whose members 110 the rope may travel, one clutch member being carried by the sheave frame work, the other clutch member being swingingly connected at one end with the carriage, and link mechanism connecting the latter clutch member with the swinging frame work, whereby the frame work causes separation of the clutch members when the load is being lifted and a closing movement of the clutch when the elevated load is relieved of lifting force, 115 120 the distance between the axes of movement of the frame work and the swinging clutch member being substantially equal to the distance between the points of union of the link mechanism with the frame work and swinging clutch member, whereby the gripping surfaces of the clutch members are maintained in substantially parallel relation throughout the relative movements of the clutch members. 125 130

2. In a carrier, the combination with a carriage, of a draft rope for lifting the load, a pair of draft rope engaging sheaves, a frame work for said sheaves having swinging mounting upon the carriage at a location between said sheaves, the parts being so related that the draft rope swings the frame work in one direction when pull is exerted thereon to lift the load, and swings the frame work in the opposite direction when the elevated load is relieved of lifting force, a draft rope clutch between whose members the rope may travel, one clutch member being carried by the sheave frame work, the other clutch member being swingingly connected at one end with the carriage, and link mechanism connecting the latter clutch member with the swinging frame work, whereby the frame work causes separation of the clutch members when the load is being lifted and a closing movement of the clutch when the elevated load is relieved of lifting force.
3. In a carrier, the combination with a carriage, of a draft rope for lifting the load, a pair of draft rope engaging sheaves, a frame work for said sheaves having swinging mounting upon the carriage at a location between said sheaves, the parts being so related that the draft rope swings the frame work in one direction when pull is exerted thereon to lift the load, and swings the frame work in the opposite direction when the elevated load is relieved of lifting force, a draft rope clutch between whose members the rope may travel, one clutch member being carried by the sheave frame work and the other by the carriage, and a connection between said frame work and the latter clutch member, whereby the frame work causes separation of the clutch members when the load is being lifted and a closing movement of the clutch when the elevated load is relieved of lifting force.
4. In a carrier, the combination with a carriage, of a draft rope for lifting the load, a sheave structure swingingly mounted upon the carriage and serving to be moved by said rope in one direction when the load is being lifted and serving to be moved in the reverse direction by the elevated load when relieved of lifting force, a draft rope clutch having one member provided upon the frame work and the companion member mounted upon the carriage, and a connection intervening between the frame work and the latter clutch member, whereby when the frame work is moved by the rope when the rope is pulled to lift the load, the clutch members will be separated, and whereby when the said frame work is moved reversely, when the elevated load is relieved of lifting force, closing movement of the clutch is effected.
5. In a carrier, the combination with a carriage, of a draft rope for lifting the load, a sheave structure carrying a sheave over which the rope passes in leaving the carrier, said sheave structure being swingingly mounted upon the carriage and serving to be moved by said rope in one direction when the load is being lifted, and serving to be moved in the reverse direction by the elevated load when relieved of lifting force, and a draft rope clutch brought into braking engagement with said rope by the frame work when the frame work is moved by the elevated load upon the removal of lifting force from the load, and released from braking engagement with the rope when the frame work is moved as a consequence of pull thereupon to lift the load.
6. In a carrier, the combination with a carriage, of a draft rope for lifting the load, a sheave structure carrying a sheave over which the rope passes in leaving the carrier, said sheave structure being movably mounted upon the carriage and serving to be moved by said rope in one direction when the load is being lifted, and serving to be moved in the reverse direction by the elevated load when relieved of lifting force, and a draft rope clutch brought into braking engagement with said rope by the frame work when the frame work is moved by the elevated load upon the removal of lifting force from the load, and released from braking engagement with the rope when the frame work is moved as a consequence of pull thereupon to lift the load.

In witness whereof, I hereunto subscribe my name this 11th day of July A. D. 1908.

FRANK S. POLLEY.
